CLAIM

The ornamental design for a control desk, substantially as shown and described.

DESCRIPTION

FIG. 1 is a perspective view of a control desk showing my design.

FIG. 2 is a front view of the control desk of FIG. 1.

FIG. 3 is a back view of the control desk of FIG. 1.

FIG. 4 is a right side view of the control desk of FIG. 1.

FIG. 5 is a left side view of the control desk of FIG. 1.

FIG. 6 is a top view of the control desk of FIG. 1; and, FIG. 7 is a bottom view of the control desk of FIG. 1.

The broken lines illustrate features that form no part of the claimed design.
